(57) **CLAIM**

The ornamental design for 3D glasses, as shown and described.

DESCRIPTION

FIG. 1 is a front elevational view of 3D glasses showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and

FIG. 7 is a perspective view thereof;

FIG. 8 is a front elevational view of the 3D glasses in a state of use;

FIG. 9 is a rear elevational view of the 3D glasses shown in FIG. 8;

FIG. 10 is a left side view of the 3D glasses shown in FIG. 8;

FIG. 11 is a right side view of the 3D glasses shown in FIG. 8;

FIG. 12 is a top plan view of the 3D glasses shown in FIG. 8;

FIG. 13 is a bottom plan view of the 3D glasses shown in FIG. 8; and,

FIG. 14 is a perspective view of the 3D glasses shown in FIG. 8.

The broken lines shown in the drawings are included for the purpose of illustrating unclaimed portions of the 3D glasses and form no part of the claimed design.

1 Claim, 8 Drawing Sheets
